UNITED STATES PATENT OFFICE.

JOHN WILLIAM BOYD, OF MISHAWAKA, INDIANA, ASSIGNOR OF ONE-HALF TO
HENRY O. KREMER, OF MISHAWAKA, INDIANA.

FISHING-ROD SUPPORT.

1,013,734.

Specification of Letters Patent.

Patented Jan. 2, 1912.

Application filed June 26, 1911. Serial No. 635,341.

To all whom it may concern:

Be it known that I, JOHN WILLIAM BOYD, a citizen of the United States, residing at Mishawaka, in the county of St. Joseph and State of Indiana, have invented new and useful Improvements in Fishing-Rod Supports, of which the following is a specification.

My invention relates to improvements in fishing-rod supports in which a suitable rod holder is provided, adjustably secured to a standard having a clamp adapted to be secured at the margin of the seat or gunwale of a boat or other suitable location.

The objects of my invention are to provide a support of the character described in which the simplicity of construction is consistent with the durability of the device.

Further objects of my invention are to provide a rod holder which is adapted to hold the rod in different desired positions, or to so pivot the rod holder, and provide stops that the rod will, upon movement of the boat, so position itself that the bait end of the fish line will be positioned remote from the boat.

I attain these objects by the construction and arrangements of parts shown in the accompanying drawing, in which,—

Figure 1 is a perspective view of a device embodying my invention. Fig. 2 is a vertical sectional view taken on the line 2—2 of Fig. 1. Fig. 3 is a cross sectional view taken on the line 3—3 of Fig. 1, looking in the direction of the arrow. Fig. 4 is a fragmentary perspective view similar to Fig. 3. Fig. 5 is a diagrammatic view showing the automatic positioning of the rod according to the direction of movement of the boat.

Similar characters refer to similar parts throughout the several views.

In the drawings, 3 represents a clamp, provided with the usual yoke 4 and clamp screw 5, adapted to be secured at the margin of a seat or gunwale of a boat. The yoke 4 has formed on its outer margin an adjusting disk 6 provided with a plurality of apertures 7 formed in the face thereof.

A standard 8 is provided, pivoted to the clamp 3 at 9 and has formed at its one end an adjusting disk 10, provided with a plurality of apertures 11, which co-act with the adjusting disk 6, by the aid of a cotter-pin 12, to retain standard 8 in the desired

adjusted position with respect to the clamp. 55 The upper end of the standard 8 is provided with a sector plate 13, provided with a plurality of apertures 14, concentric to which is pivotally mounted a rod holder 15 including a forked end 16 and hooked end 17. 60 The rod holder carries a cotter pin 18, or other suitable stop, adapted to be inserted into any one of the apertures 14 in the sector plate 13, to retain the rod holder in the desired adjusted position with respect to the 65 standard as shown in Fig. 3, or to be positioned so that it will engage the radial margins of the sector plate as shown in Fig. 4, allowing free movement of the rod holder through an angle included between the said 70 radial margins, the purpose of which will be described in connection with the operation of the device, which is as follows:—

When it is desired to set up the device for use, the clamp 3 is secured to any suitable 75 portion of the boat, such as the vertical gunwale as shown in Fig. 5, and the angle to which the fishing rod is to lie with respect to the horizontal is adjusted by means of the disks 6 and 10, their registering apertures 80 and the cotter pin 12. When it is desired to retain the rod holder in a fixed position with respect to the boat the cotter pin 18 is inserted in one of the apertures 14 of the sector plate 13. The handle of the fishing rod 85 is carried by the forked and hooked portions of the holder 15. When fishing, it is desirable that the bait be as far as possible from the boat and in order to obtain an automatic positioning of the rod with the bait 90 on the fish line at a distance from the boat and upon movement thereof, the cotter pin is inserted to engage either of the radial margins of the sector plate as shown in Fig. 4, the action upon the rod being indicated 95 diagrammatically in Fig. 5. In this figure 19 represents a portion of a boat moving in direction of the arrow. The resistance of the line in the water draws the fishing pole 20 to the position shown in full lines whereupon the bait is located remote from the boat. A movement of the boat in the opposite direction would cause the pole to assume a position as shown in dotted lines because of the free movement of the rod holder with 100 respect to its support through an angle of predetermined magnitude. This automatic positioning of the rod is very desirable 105

when fishing in the manner termed "skipping."

I claim:

1. A fishing-rod support comprising in combination, a clamp provided with a disk having a plurality of apertures, a standard provided with a disk having a plurality of apertures, said clamp and standard being pivoted to each other concentrically with the 10 said disks, a pin adapted to be inserted through two registering apertures in the said disks to retain the standard in an adjusted position; a sector plate carried by said standard and having a plurality of 15 apertures arranged in an arc concentrically thereto, a rod holder pivotally mounted concentric to said sector, and a pin carried by said rod holder adapted to be inserted into any of the said apertures in said sector, or 20 to be inserted to engage either of the radial margins of said sector permitting free oscil-

latory movement of said rod holder through an angle of predetermined magnitude.

2. In a fishing rod support, the combination with a clamp adapted to be secured to 25 the seat or gunwale of a boat, of a standard adjustably carried by said clamp and provided with a sector having a plurality of apertures therein, a rod holder pivotally carried by said support, and a stop, carried 30 by said rod holder, adapted to be inserted into any of the said apertures, or to be inserted to engage either of the radial margins of said sector permitting free oscillatory movement of said rod holder through an angle of predetermined magnitude. 35

In testimony whereof I affix my signature in presence of two witnesses.

JOHN WILLIAM BOYD.
